DESIGN FOR A CHAIR

William H. Brown and Samuel W. Young,
Wilton, Conn.

Application May 26, 1942, Serial No. 107,006

Term of patent 14 years

To all whom it may concern:

Be it known that we, William H. Brown and Samuel W. Young, citizens of the United States, residing at Wilton, in the county of Fairfield and State of Connecticut, have invented a new, original, and ornamental Design for Chairs, of which the following is a specification, reference being had to the accompanying drawing, forming part thereof.

Fig. 1 is a perspective view of a chair, showing our new design,

Fig. 2 is a top plan view of the chair, on a reduced scale;

Fig. 3 is a side elevational view; and
Fig. 4 is a front elevational view thereof.

We claim:

The ornamental design for a chair, as shown.

SAMUEL W. YOUNG.
WILLIAM H. BROWN.
